UNITED STATES PATENT OFFICE.

JOHN J. YOUNG, OF DENVER, COLORADO.

DIE-STARTER.

1,042,995.

Specification of Letters Patent.

Patented Oct. 29, 1912.

Application filed April 27, 1910. Serial No. 557,894.

To all whom it may concern:

Be it known that I, JOHN J. YOUNG, a citizen of the United States, residing at Denver, in the county of Denver and State 5 of Colorado, have invented certain new and useful Improvements in Die-Starters; and I do declare the following to be a full, clear, and exact description of the invention, such as will enable others skilled in the art to 10 which it appertains to make and use the same.

This invention relates to improvements in die starters.

One object of the invention is to provide 15 a device of this character whereby a die may be readily engaged with the end of a pipe and started in the operation of cutting a thread on the latter with or without the use of a stock.

Another object is to provide a starter of 20 this character having means whereby the same may be firmly secured to a pipe for holding the die in operative engagement therewith.

With these and other objects in view, the 25 invention consists of certain novel features of construction, combination, and arrangement of parts as will be more fully described and particularly pointed out in the appended 30 claims.

In the accompanying drawings: Figure 1 is a vertical longitudinal section of a pipe showing the application of my improved 35 starter and a die thereto; Fig. 2 is a cross sectional view of the same on the line 2—2 of Fig. 1; Fig. 3 is a longitudinal section of the starter removed from the pipe.

My improved die starter comprises a cylindrical body portion 1 the diameter of 40 which corresponds substantially to the inside diameter of the pipe with which it is to be engaged. The outer body 1 is threaded as shown at 2 and said threaded outer portion has a diameter corresponding to the 45 outside diameter of the pipe to which the starter is to be applied. On the threaded outer end of the die is formed a reduced extension 3 having arranged thereon a suitable handle 4. The body portion 1 is provided 50 with a centrally disposed circular bore 5 the outer portion of which in the extension 3 is of less diameter than the main portion and said reduced portion is threaded to receive an expanding screw 6 having a conically shaped inner end 7. The outer end of

the screw 6 is provided with a head 8 carrying a handle 9.

In the body portion 1 of the starter is formed a series of transverse radially disposed passages 10 of which there may be any suitable number and in said passages are slidably mounted fastening pins 11 having pointed outer ends 12 and beveled inner ends 13. The beveled inner ends 13 of the pins project into the bore 5 and are adapted to 65 be engaged by the conical inner end of the expanding screw 6 whereby when the latter is screwed into the starter said pins will be forced outwardly and the pointed outer ends thereof forcibly engaged with the inner 70 surface of the pipe with which the starter is engaged thus securely holding the starter in position. In each of the pins 11 is formed a notch or recess 14 said recess being adapted 75 to receive stop pins 15 which are inserted through the side of the body portion 1 of the starter. The pins 15 when thus engaged with the slots 14 limit the movement of the pins 11 and prevent the same from dropping or being forced out of the passages 10. 80

In the operation of the device the body portion of the starter is inserted in the end of the pipe and expanding screw 6 then turned in the proper direction to force the pins 11 into engagement with the inner surface of the pipe thus securely fastening the starter in place. After the starter has thus been secured in the end of the pipe the threading die 16 which when in operative 85 position is engaged with the enlarged threaded portion 2 of the body is turned by means of a stock or wrench in the proper direction for screwing the same forwardly or onto the end of the pipe and from off the threaded portion of the starter thereby cutting the threads of the outer surface of the pipe. The unscrewing of the die from the threaded portion 16 of the starter will feed the die onto the pipe as it cuts the thread thereon. After two or three threads have 90 been cut on the end of the pipe the fastening pins 11 may be released and the starter screwed back out of the die by means of the handle 4.

By means of my improved starter the die 105 may be operated to cut the threads on a pipe by means of a wrench and without the necessity of employing a stock which in many instances cannot be employed for turning the die thus necessitating the use of a 110

wrench or similar instrument. My improved starter will also be found useful in connection with the threading of large sized pipes or with pipes having broken or uneven ends wherein the starting of a die in the usual manner is extremely difficult.

From the foregoing description taken in connection with the accompanying drawings, the construction and operation of the invention will be readily understood without requiring a more extended explanation.

Various changes in the form, proportion and the minor details of construction may be resorted to without departing from the principle or sacrificing any of the advantages of the invention as defined in the appended claims.

Having thus described my invention, what I claim is:

20. 1. In a die starter, a body portion having a part adapted to enter a pipe to be threaded, while one part of the body portion extends beyond said pipe and is threaded to receive a die, the threaded part of the body portion being of the same diameter as the pipe to be threaded, and means mounted on and carried by the body portion for locking the latter against turning in the pipe during the performance of the thread-starting function.

2. A plug having a portion adapted to enter a pipe and an enlarged threaded portion extending beyond the pipe-entering portion, adapted to receive a die, the die-holding portion being of the same diameter as the outside diameter of the pipe to be threaded, a stem threaded in the plug, and means carried by the plug and arranged to be actuated by the stem for locking the plug within the pipe.

3. In a die starter, a body portion adapted to be engaged with the end of a pipe to be threaded, fastening pins arranged in said body portion, means to project said pins into operative engagement with the pipe to hold the starter in position thereon and a threaded die receiving portion formed on said starter whereby a die is fed into operative engagement with a pipe to cut the threads thereon.

4. In a die starter a body portion adapted to be engaged with a pipe to be threaded, fastening pins arranged in said body portion, an expanding screw adapted to force said pins outwardly and into engagement with the inner surface of the pipe whereby the starter is held in engagement therewith, means to limit the movement of said pins and an enlarged threaded die receiving portion whereby the die may be fed forward into operative engagement with the outer surface of a pipe for the purpose of cutting threads thereon.

5. A thread-starter for pipe, comprising a plug adapted to extend into the end of

said pipe, a threaded stem arranged to be screwed in and out of said plug a short distance, cam dogs mounted on the end of said plug that extends into the pipe, and arranged to be actuated by said stem to cause 70 said dogs to engage and to grip the inner surface of said pipe, a threaded collar portion on the outer end of said plug of substantially the same diameter as the outside diameter end of said pipe, and arranged to bear against the end of said pipe and arranged to receive a die adapted to cut a thread on said pipe.

6. A thread-starter for starting threads on pipes, comprising a plug adapted to extend into a pipe, a threaded collar portion adapted to bear against the end of the plug and provided with a thread of the same size and pitch as the thread that is to be cut on the end of the pipe, and adapted to receive the thread-cutting die that is adapted to cut the thread on the pipe, with a stem extending through said plug and threaded to it, cam dogs mounted in said plug and arranged to be actuated by said stem to engage 90 and grip the inner surface of said pipe, and a hand-wheel secured to the outer end of said stem and arranged to rotate said stem to actuate said cam dogs to grip the inner surface of said pipe when the stem travels 95 in one direction, the cam dogs being arranged to be released when the stem travels in the opposite direction.

7. In a thread-starter for pipe, the combination of a plug provided with a thread arranged to receive a thread-cutting die so that said thread-cutting die can be screwed from said plug's thread on to said pipe in such a manner as to start a thread thereon, and means including cam dogs and a threaded rod mounted on said plug, the threaded rod being arranged to actuate the dogs, for securing said plug to said pipe.

8. A plug having a portion adapted to enter a pipe and an enlarged threaded portion extending beyond the pipe-entering portion and adapted to receive a die,—the die-holding portion being of the same diameter as the outside diameter of the pipe to be threaded, and means carried by the plug for locking the latter within the pipe.

9. A plug having a portion adapted to enter a pipe and an enlarged threaded portion extending beyond the pipe-entering portion and adapted to receive a die, the die-holding portion being of the same diameter as the outside diameter of the pipe to be threaded, and means carried by said plug for holding the latter against turning within the pipe during the performance of the 125 thread-starting function.

10. A plug having a portion adapted to enter a pipe and an enlarged threaded portion extending beyond the pipe-entering portion, the enlarged portion being adapted 130

to receive a die, the die-holding portion being of the same diameter as the outside diameter of the pipe to be threaded, a stem carried by the plug and means actuated by 5 the stem for locking the plug within the pipe.

In testimony whereof I have hereunto set

my hand in presence of two subscribing witnesses.

JOHN J. YOUNG.
